UNITED STATES PATENT OFFICE.

LOUIS WOJIDKOW, OF BROOKLYN, NEW YORK.

DESIGN FOR A COFFEE-POT.

SPECIFICATION forming part of Design No. 26,436, dated December 22, 1896.

Application filed November 13, 1896. Serial No. 612,031. Term of patent 31 years.

To all whom it may concern:

Be it known that I, LOUIS WOJIDKOW, a citizen of the United States, residing at Brooklyn, in the county of Kings and State of New York, have invented and produced a new and original Design for Coffee-Pots, of which the following is a specification, reference being had to the accompanying drawing, which shows the same in perspective.

10 The leading feature of my design consists of the particular outline or contour of the article, the body of which is somewhat of a barrel shape, the top or lid rising therefrom in

compound curve and terminating in a knob, and a fanciful base. 15

A represents the barrel-shaped body, having the fanciful base B and a top C, rising in compound curve and terminating in the knob D.

E represents the handle, and F the spout.

What I claim is—

20 The design for a coffee-pot, as shown and described.

LOUIS WOJIDKOW.
